Thos. S. Norden Design for combined Ink stand, Suspender-Clip and Pen

No. 2937

PATENTED
FEB 18 1868

United States Patent Office.

THOMAS S. HUDSON, OF EAST CAMBRIDGE, MASSACHUSETTS.

Design No. 2,937, dated February 18, 1868.

DESIGN FOR AN INKSTAND, SPONGE-CUP, AND PEN-RACK.

The Schedule referred to in these Letters Patent and making part of the same.

ALL WHOM IT MAY CONCERN:

Be it known that I, THOMAS S. HUDSON, of East Cambridge, in the county of Middlesex, and State of Massachusetts, have invented a new Design for a Combined Inkstand, Sponge-Cup, and Pen-Rack, of which following is a full, clear, and exact description, reference being had to the accompanying drawings, in which are represented perspective views of my design.

The object of my invention is to produce an ornamental and unique design for an inkstand, sponge-cup, pen-rack; and consists in two or more circular receptacles for holding the ink and sponge, in combination with one or two curved shelves for holding the pens.

To enable others skilled in the art to understand and use my invention, I will proceed to describe the manner in which I have carried it out.

In the said drawings, A B C represent three circular receptacles, the upper portions of which project slightly above the surface of the stand. The central receptacle C is designed to hold a sponge saturated with water, while the two outside receptacles A B are provided with covers a, and are intended to receive ink of the same or different colors. On one side of the stand projects a curved trough or shelf, D, of the form seen, which serves as a repository for pens with their handles, when not in use. E, fig. 2, is a cover for the sponge-receptacle C.

By placing a pen-rack, D, on each side of the receptacles A B C, and using removable instead of stationary covers a, or reversing the cover to one of them, the above-described apparatus is suitable for use for a double desk.

Claim.

What I claim as my invention, and desire to secure by Letters Patent, is—

The within-described design for a combined inkstand, sponge-cup, and pen-rack, substantially as shown.

THOS. S. HUDSON.
